DESIGN FOR A LAMP BASE

Henry A. Perlmutter, Brooklyn, N. Y.

Application December 19, 1935, Serial No. 60,167

Term of patent 3½ years

To all whom it may concern:

Be it known that I, Henry A. Perlmutter, a citizen of the United States of America, residing in Brooklyn, county of Kings, and State of New York, have invented a new, original, and ornamental Design for a Lamp Base, of which the following is a specification, reference being had to the accompanying drawing, forming part thereof.

Figure 1 is a side elevational view of a lamp base showing my new design.

Figure 2 is a plan view of a lamp base as shown in Figure 1. The ornamentation on the lamp base is not completely shown, it being understood that the completion thereof would involve a mere repetition of the part shown.

The opposite side of Fig. 1 is substantially like the side shown.

I claim:

The ornamental design for a lamp base, substantially as shown and described.

HENRY A. PERLMUTTER.
